(57) **CLAIM**

The ornamental design for an uninterruptable power supply, as shown and described.

DESCRIPTION

FIG. 1 is a perspective view showing our new design;

FIG. 2 is a top plan view thereof;

FIG. 3 is a bottom plan view thereof;

FIG. 4 is a side view thereof;

FIG. 5 is a side view thereof;

FIG. 6 is an end view; and,

FIG. 7 is an end view.

The portions of the uninterruptable power supply shown in broken lines are for illustrative purposes only and form no part of the claimed design.
